UNITED STATES PATENT OFFICE

119,213

DESIGN FOR A DRESS

Morris Green, Brooklyn, N. Y.

Application January 13, 1940, Serial No. 89,448

Term of patent 3½ years

To all whom it may concern:

Be it known that I, Morris Green, a citizen of the United States, residing at Brooklyn, in the County of Kings and State of New York, have invented a new, original, and ornamental Design for a Dress, of which the following is a specification, reference being had to the accompanying drawing, forming part thereof, wherein—

Fig. 2 is a back view thereof.

I claim:

The ornamental design for a dress, substantially as shown.

MORRIS GREEN.
